(No Model.)

L. M. HOOPER.
CLOSET PULL ATTACHMENT.

No. 529,123.

Patented Nov. 13, 1894.

THE NORRIS PETERS CO., PHOTO-LITHO., WASHINGTON, D. C.

UNITED STATES PATENT OFFICE.

LOUIS M. HOOPER, OF RUTHERFORD, NEW JERSEY, ASSIGNOR TO THE
J. L. MOTT IRON WORKS, OF NEW YORK, N. Y.

CLOSET-PULL ATTACHMENT.

SPECIFICATION forming part of Letters Patent No. 529,123, dated November 13, 1894.

Application filed February 8, 1894. Serial No. 499,435. (No model.)

To all whom it may concern:

Be it known that I, LOUIS M. HOOPER, a citizen of the United States, residing at Rutherford, in the county of Bergen and State of New Jersey, have invented an Improvement in Closet-Flushing Attachments, of which the following is a specification.

In water closets, especially those used in factories and public buildings, it is desirable to insure the flush of the basin each time the closet is used. Automatic devices have heretofore been constructed in which the movement of the seat has operated the valve of the cistern, and in some instances compound levers have been employed upon the bracket or leg supporting the seat plate, and in other instances a chain has passed down around a pulley upon the floor, the seat having a weight at the rear for partially elevating the same. This invention may be used with any closet, but it is especially adapted to porcelain closets where a weight for elevating the seat would be liable to injure the porcelain and where a connection to a pulley upon the floor is objectionable as liable to get out of order and to interfere with cleanliness.

The object of the present improvement is to actuate the valve or valves of the cistern by a backward pressure exerted by the seat as the same is brought down to rest upon the closet, the lever that is connected with the cistern valve being pivoted at or upon the seat plate or place where the seat itself is hinged, so that the entire device for actuating the cistern valve is supported by the closet, and at the same time the seat is free to be raised up and swung back whenever desired without operating the valve in the cistern.

In the drawings, Figure 1 is an elevation of the actuating mechanism, the seat plate and a portion of the seat being represented in section. Fig. 2 is a plan view of the metallic portion of the valve actuating device. Fig. 3 is a section at the line $x-x$ of Fig. 2. Fig. 4 shows a modification in the position of the parts that actuate the cistern pull. Fig. 5 is a plan view of the same. Fig. 6 is an elevation of a slightly different shape of actuating lever, and Fig. 7 is a plan view of the same.

A portion of the closet bowl is represented

at A having a rearward projection or shelf 2 to which the seat plate B is connected by any suitable device such as the bolts 3, and the hinge C unites the seat plate B to the seat D. These parts do not form any portion of my 55 invention but are introduced to show how my devices are applied.

The rod or chain at E is to be extended up and connected with the lever in the supply cistern, and the cistern is to be of any desired construction so that the flushing of the closet is effected by a pull upon the rod E or by a pull upon the chain taking the place of the rod.

The valve connection E is made to the lever F that is pivoted at 4 to a plate G, preferably connected to the under side of the wooden seat plate B shown in Fig. 1, and this lever F is advantageously made tubular so that the rod 6 to which the valve connection E is connected may be moved out or in and clamped by the screw 7 so as to bring the end of the rod 6 and the valve connection E to the desired proximity to the wall, and the lever F is represented in Fig. 1 as bent at right angles and with the actuating bolt H connected with the bent end of the lever at 9, and such bolt H passes through the vertical portion of the plate G and projects sufficiently to be acted upon by the back edge of the seat D, which back edge is preferably armed with a plate I that forms an unyielding surface to act upon the bolt.

It will now be understood that the parts are represented in Fig. 1 in their normal position with the seat partly raised, and as soon as the seat is depressed so as to rest on and be supported by the closet, the bolt H is forced backwardly, and by the bent lever F the valve connection E is moved to actuate the valve or valves of the cistern, and when the seat D is liberated the parts reassume their normal position, and according to the character of the valve in the water closet cistern, so the water will be allowed to run and flush the closet when the seat is depressed or when it is allowed to rise; and I remark that the seat D can be swung up on the hinges C as usual to give free access to the closet bowl.

It will be observed that in introducing this 100

improvement, the wooden seat plate B is sufficiently recessed for the reception of the lever and the actuating parts thereof.

In Figs. 4 and 5 the valve connection E and rod 6 are similar to those before described, but the lever F' is nearly straight and pivoted at 14 to a plate upon the top of the seat plate B, and the end of the lever F' near the seat D is forked for the reception of one end 10 of the bent lever K that is pivoted at 11 upon a plate or bearing connected with the seat plate B, such seat plate being recessed on its upper surface for the reception of the parts instead of the lower surface, and the bent 15 lever K is acted upon by the downward movement of the seat D to actuate the valve connection E leading to the cistern; and in Figs. 6 and 7 the valve connection E, rod 6 and tubular lever F' are the same as shown in 20 Fig. 4, but the forked end of such lever F' is within a recess at the lower side of the seat plate B instead of the upper side, and a bent lever K' is made use of for actuating the forked end of the lever F'. This bent lever 25 K' is preferably pivoted upon the pin of the hinge C', one leaf of such hinge C' being connected to the seat D and the other leaf to the seat plate B, and the bent lever K' is central between the knuckles of the hinge 30 C' and passes down into a recess excavated in the wood of the seat plate, and the back end of such bent lever K passes into the jaw at the end of the lever F', and when the seat is depressed the bent lever K' moves 35 the contiguous end of the lever F' and actuates the valve connection E at the other end. It will be apparent that in all these instances the levers actuating the cistern pull are pivoted upon the seat plate and they are actuated 40 by a backward thrust from the back edge of the seat, and the seat is free to be swung up or down in the usual manner and it is partially elevated when in the normal condition by the rod or chain E that is connected 45 to the weighted lever in the closet cistern as usual. If the cistern is so constructed that the flushing is effected when the connection E is moved upwardly, the lever K', Fig. 6, may be extended back, as

shown by dotted lines, and the connection E 50 attached directly thereto. These parts are simple and not liable to get out of order, and can be made more or less ornamental, and in the positions represented in Figs. 1 and 6, they are scarcely noticeable in consequence 55 of being beneath the seat plate, and under all circumstances they can be made ornamental by plating or otherwise finishing them.

I do not limit myself to the use of the present attachment with a seat plate that is of 60 wood, as the seat plate may be of metal or any other suitable material, and when a metallic seat plate or hinge connection of the seat to the porcelain of the closet is made use of, the present device will usually be upon 65 the surface of such metallic seat plate or connection, as represented in Fig. 5, instead of coming beneath the same.

I claim as my invention—

1. The combination with the wire or chain 70 extending to the cistern and by which the valve is actuated, of a lever, to the long end of which such wire or chain is connected, a pivot for the lever and a support for the same upon the water closet, the closet seat and a 75 connection therefrom to the short end of the lever whereby the long back end of the lever is drawn down as the closet seat is pressed down upon the closet substantially as specified. 80

2. The combination with the wire or chain extending to the cistern and by which the valve is actuated, of a bent lever, to the long end of which such wire or chain is connected, a pivot for the lever and a support for the 85 same upon the water closet, the closet seat and a bolt connected at one end to the short arm of the lever and acted upon at the other end by the seat whereby the long back end of the lever is drawn down as the closet seat 90 is pressed down upon the closet, substantially as specified.

Signed by me this 31st day of January, 1894.

L. M. HOOPER.
